CLAIM

The ornamental design for a helmet carrier, as shown and described.

DESCRIPTION

FIG. 1 is a front view of a helmet carrier showing my new design;

FIG. 2 is a rear view of the helmet carrier;

FIG. 3 is a right side view of the helmet carrier;

FIG. 4 is a left side view of the helmet carrier;

FIG. 5 is a top view of the helmet carrier;

FIG. 6 is a bottom view of the helmet carrier;

FIG. 7 is a top front side perspective view of the helmet carrier; and,

FIG. 8 is a top front side perspective view of the helmet carrier in an alternate position.

The broken lines shown on the helmet carrier are for the purpose of illustrating environmental structure, and form no part of the claimed design.
